VARIABLE CURRENT TRANSFORMER
SYSTEM

Uno Lamm and Harry Forssell, Ludvika, Sweden,
and Johannes Hansen, Milwaukee, Wis., as-
signors to Allmanna Svenska Elektriska Aktie-
bolaget, Västerås, Sweden, a corporation of
Sweden

Application September 3, 1948, Serial No. 47,564
In Sweden June 22, 1942

Section 1, Public Law 690, August 8, 1946
Patent expires June 22, 1962

5 Claims. (Cl. 323—48)

1

This application is a continuation in part of application S. N. 493,210, filed July 2, 1943, now abandoned.

Transformers having a high and preferably adjustable leakage have, as is well-known, obtained a vast use among others for welding purposes. They have hitherto most frequently been so constructed that the primary and secondary windings have been mounted on the different outer legs of a three-legged core, the middle leg of which has contained adjustable air gaps. It has, however, been found that this way affords no possibility of adjusting the secondary short-circuit current between wide limits and still keeping the secondary voltage substantially constant, as is generally desirable. According to the present invention, the secondary winding of the transformer is therefore divided into two or more parts, the leakage fluxes of which are substantially independent of one another, and which winding parts can be connected individually or severally in parallel to the load for a coarse adjustment of the secondary short-circuit current. A fine adjustment of the said current is at the same time obtained by variable impedance means included in the current path of one of said winding parts.

We are aware that it has been proposed to regulate the no load voltage of welding transformers by connecting a larger or smaller number of secondary turns in series, and also to use certain winding parts on the transformer core, which have a large leakage with respect to the primary winding, as series inductances for regulating the current. The present invention provides for a much wider range of regulation of the short-circuit current without affecting the no-load voltage by connecting in parallel different numbers of winding parts having a large leakage which determines the short-circuit current of each part individually, independent of the current in the other parts.

Two forms of the invention are illustrated in section in Figs. 1 and 2 of the accompanying drawing, while Fig. 3 shows a third form.

In Fig. 1, all the parts of the transformer are stationary, while the fine adjustment is effected by means of an adjustable external series inductance. 1 is the rectangular transformer core and 2 the primary winding, which comprises two coils on each of two opposite sides of the core. The secondary winding is also divided into several coils, two of which, designated by 3 and 4, are mounted on the two remaining rectangle sides of the core, thus have a large leakage with re-

2

spect to the primary winding, while two pairs of secondary coils 5, 6 lie closely adjacent to the primary winding, thus with a small mutual leakage. Between the coil 3 and the load 10, an external, constant reactance 7 may be connected, and between the pair of coils 6 and the load there may be connected a reactance 8, adjustable for instance by means of a superposed direct current for a fine adjustment of the secondary short-circuit current.

The different steps of the coarse adjustment are obtained by closing one or more of the switches 9. The first step, corresponding to the smallest secondary current, is represented by secondary coil 3 alone, connected in series with the external reactance 7. The coil 3 then embraces only such a part of the primary flux which is necessary for overcoming the reactance 7, while the rest closes through the air at the bottom. (The voltage drop of the load is here neglected, as in welding transformers the pure short-circuit case must always be taken into account.) To the secondary current thus obtained, the finely adjustable current is added which flows from the winding 6 through the adjustable reactance 8.

The next step of the coarse adjustment is obtained by bridging the reactance 7 so as to make the coil feed the load directly. The primary flux is then entirely closed through the air at the bottom.

For the next step, the windings 5 and 4 are connected in series to the load. The winding 5, which has a small leakage with respect to the primary winding, always generates a voltage, which in the case of full short-circuit must be counteracted by the winding 4. The latter therefore must be traversed by a flux opposite to that of the primary current, corresponding to a higher secondary current than that which can be produced by the winding 3 alone.

Further coarse adjusting steps can be obtained by connecting the winding 4 in parallel to the winding 3, with or without the series reactance 7. For each coarse adjusting step, a fine adjusting can be obtained in the manner already described by the reactance 8.

In Fig. 2, all the secondary windings are mounted on the same sides of the substantially rectangular transformer core 11 as the primary windings 12, but some parts 13, 14 of the secondary windings are mounted at a comparatively large distance from the primary windings, and between the parts 13 and 14 the core has a projection 21 for increasing the leakage. In the space between one secondary winding 14 and the

primary winding, there is a wedge-shaped core portion 22 which is supposed to be adjustable perpendicularly to the plane of the drawing for a fine adjustment of the leakage path around the winding 14. In the most extracted position of the wedge-shaped core portion 22, the leakage distance between the corresponding rectangle side and the projection 21 is assumed to be somewhat larger than between the latter and the opposite rectangle side. Two other portions 15, 16 of the secondary winding are mounted nearer the primary winding so as to have a smaller leakage reactance. All the portions of the secondary winding can be successively connected in parallel by switches 13a-16a to feed the load 20.

If the secondary winding 14 is connected in circuit alone by switch 14a and the airgap in the leakage path between the said winding and the primary winding is gradually increased from zero to its maximum value by extracting the wedge 22, the short-circuit current rises continuously from nearly zero to a value which may be designated by 1. If also the winding 13 is connected to the load by switch 13a, the current may, by repeating the same fine-adjustment operation, be gradually raised from 1 to 2. The windings 15 and 16, which have a smaller leakage with respect to the primary winding, may each represent the current 2, and thus the whole adjustment range will be continuous from 0 to 6, the last one when all the secondary windings are connected in parallel respectively, by switches 15a and 16a, and the wedge 22 entirely extracted.

The transformer according to the present invention may cooperate with a rectifier, and especially in this case it may be advisable to make it three-phase. In a three-phase transformer it is generally, with respect to the symmetry, most advisable to mount all the windings on the legs of the three-legged core, thus essentially in analogy with Fig. 2, but to effect the fine adjustment by an adjustable inductance, for instance by a transductor (an inductance adjustable by superposed direct current) in analogy with Fig. 1. In a three-phase connection, there is a further possibility of adjusting the leakage besides those possible in a single-phase connection, namely, a series-connection of two secondary winding phases, which increases the reactance without increasing the no-load voltage. Such a connection is indicated in Fig. 3, in which 32 are the three primary windings of a three-phase transformer having a three-legged iron core 37. The connections of said primary windings to the feeding three-phase line are not shown, in order to simplify the diagram, but may be in any usual manner, as in star or delta. Each leg of the core carries three secondary windings. One of these, designated by 38, is situated close to the primary winding, corresponding to the winding 6 in Fig. 1, and is connected in series with a variable reactor 39, represented only in the conventional manner with an arrow to illustrate the variability. Another secondary winding 33 is situated at the top of the core at a comparatively large distance from the primary winding, and a third secondary winding 34 is situated at the bottom of the core at a still larger distance from the primary winding. The three secondary windings should have equal numbers of winding turns but may have different sectional areas of the conductors, corresponding to the different maximum or short-circuit currents to be carried thereby.

The secondary windings 33 are connected together at one end to form a neutral point 40. 75

At the other end, they are connected to switches 41. The windings 34 are connected at one end—corresponding in voltage respect to the first-named end of windings 33—each to a double-throw switch 42, by which they may be connected either to a neutral point 44 or to the free ("lower") ends of windings 33 of another phase. The lower ends of windings 34 are connected to switches 43, by which they may be connected separately or in parallel to the windings 33 to a three-phase two-way rectifier 35, between the direct current terminals of which the load 38 is connected.

When all the switches 41, 42 are open, the load 15 is fed only by the windings 38 through the variable reactors 39 and the rectifier 35. (In some cases, depending on the nature of the reactors, it may be advisable to employ a separate rectifier for the windings 38, connected in parallel to the rectifier 35 on the direct current side.) The current from the windings 38 may be regulated from zero up to a predetermined value.

The next step in the regulation involves the closing of switches 43 while the two-way switches 25 42 are in their right position. The load will then be fed by the windings 33 and 34 in series, while the phase angle between the voltages of said windings is such that the vector sum of their voltages is only equal to each one of the voltage components. On the other hand, the total reactance is equal to the sum of the reactances of both windings 33 and 34, and therefore the current is rather low. In parallel to the circuits now described, the load is fed from the windings 38 through the reactors 39, which will effect a fine regulation in the manner already described.

For the next step of regulation, the two-way switches 42 are thrown over to their left position. The windings 34 are then connected to the neutral point and feed alone the load in parallel with the windings 38 adapted for the fine regulation. For the following step, the switches 43 are opened and the switches 41 closed. Then the windings 33, which are situated at a smaller distance from the primary windings than are the windings 34 and therefore have a smaller leakage reactance, feed the load in parallel to the windings 38.

For the final step, giving the highest current value, the switches 41 and 43 are both closed while the switches 42 are still in their left position. Then all the secondary windings feed the load in parallel.

We claim as our invention:

1. A transformer having a core, a primary winding on said core, a secondary winding having a plurality of parts on said core, at least two of said parts having, with respect to the primary winding and to one another, relatively large leakage fluxes, and at least one part having, with respect to the primary winding, a relatively small leakage flux, means forming a plurality of current paths each including at least one of said parts, means to vary the impedance in one of said paths, and switch means for selectively connecting various numbers of said current paths in parallel to the work, every part of the primary winding having a relatively small leakage flux with respect to a part of the secondary winding.

2. A transformer according to claim 1 in which the majority of the secondary winding parts lie on the same core parts as the primary winding but at different distances therefrom, and in which the impedance varying means comprise a variable inductance created by a movable core portion in-

terposed between certain of said secondary winding parts.

3. A transformer having a core, a primary winding on said core, a secondary winding having a plurality of parts on said core, at least two of said parts having, with respect to the primary winding and to one another, relatively large leakage fluxes, and at least one part being so disposed with respect to the primary winding as to give a relatively small mutual leakage flux, means forming a plurality of current paths each including at least one of said parts, variable inductance means connected in the current path including the secondary winding part having the smallest leakage flux with respect to the primary winding, and switch means for selectively connecting various numbers of said current paths in parallel to the work.

4. A transformer according to claim 3 comprising a rectangular transformer core, the primary winding being mounted on two opposite sides of said core, and the parts of the secondary winding

having relatively large leakage fluxes with respect to the primary winding being mounted on the two remaining sides of said core.

5. A transformer according to claim 3 comprising a threephase iron core, threephase primary and secondary windings thereon, and means for connecting in series certain secondary windings differing 120° in phase.
